UNITED STATES PATENT OFFICE.

THEODORE SMITH, OF CHICAGO, ILLINOIS, ASSIGNOR TO THEO. SMITH MANUFACTURING COMPANY, OF CHICAGO, ILLINOIS, A CORPORATION OF ILLINOIS.

TELEPHONE APPARATUS.

1,141,279.

Specification of Letters Patent.

Patented June 1, 1915.

Application filed August 14, 1905. Serial No. 274,121.

To all whom it may concern:

Be it known that I, THEODORE SMITH, a citizen of the United States, residing at Chicago, in the county of Cook and State of Illinois, have invented a certain new and useful Improvement in Telephone Apparatus, of which the following is a specification.

My invention relates to telephone apparatus, and has for its object to provide a new and improved device of this description.

My invention is illustrated in the accompanying drawing, wherein—

Figure 1 shows a device embodying the invention; Fig. 2 is a plan view of the telephone receiver and transmitter; Fig. 3 is a front view thereof as seen in the direction of the arrow (see Fig. 1) with parts omitted; Fig. 4 is a sectional view on line 4—4 of Fig. 3; Fig. 5 is a sectional view showing the spring lift device.

Like letters refer to like parts throughout the several figures.

The telephone apparatus is connected to an adjustable bracket attached to the wall, said bracket comprising an end piece A, and a laterally movable piece B mounted thereon, and to which are connected the projecting pieces C and D which are pivotally connected to a center piece E⁴ which in turn is rotatably mounted upon the part B. Associated with the pieces C and D is a frictional clamping device E and a spring lift device F. The frictional clamping device consists of two parts E¹ and E². The part E¹ is preferably fixed to the piece C, and the piece D is pivotally clamped between the parts E² and E¹ by means of a thumb screw E³ passing therethrough. The spring lift device consists of a spring F¹ inclosed in two hollow tubes F², F³ overlapping, as shown in Fig. 5. These tubes are provided with engaging parts which engage the ends of the spring so that the tension of the spring may be varied by moving them toward or from each other. The tube F² is fixed to the piece D, and the tube F³ has a screw threaded connection with a sleeve F⁴ which engages the clamping device E and is held against rotation by the projection F⁵. A lock nut F⁶ is screw threaded onto the sleeve F⁴. The tension of the spring may be varied by rotating the sleeve F³, and the lock nut may then be moved up into contact therewith to hold it in position. When the pieces C or D are moved up or down the piece D slides in the frictional clamp E, but the friction is such as to hold the parts in any given position. If, for example, the parts are moved downwardly, the frictional clamp slides toward the sleeve F³ and causes it to move toward the sleeve F², and thus compress the spring. When the device is released it will stay in this position, but by applying a slight upward pressure to it it can be moved up, the spring acting to assist in this movement. The pieces C and D are pivotally connected to a connecting piece G to which is pivotally connected a connecting link G¹. Pivotally connected to this link is a cylindrical part H provided at its end with a curved neck H¹ to which is rigidly connected the telephone transmitter H². The electric conductors for the telephone pass through the pieces B and C and G and G¹ and into the cylinder H where the proper connections are made. Associated with the cylinder H is a pivoted arm I pivoted at I¹ and provided with a switch actuating piece I² which projects into said cylinder. A signaling switch H³ is mounted upon said cylinder which is provided with a removable side piece H⁴, said signaling device being located upon said removable side piece. This side piece is held in position by the screws H⁵. Attached to the arm I is the receiver hook I³ pivotally connected thereto so as to be free to rotate, the receiver J being supported thereon. The lever I and hence the receiver hook I³ are mounted at one side of the axis K about which the receiver and cylinder H move. This construction is shown in Fig. 4. It will be seen from this figure that the said receiver hook is about 45° beyond the axis K. This construction insures the pulling out of the lever I by the receiver in all its various positions so as to keep the contact lever I² in position to insure the proper circuit connections. The curve of the neck H¹ is such that although the receiver hook is pivoted above

the pivot about which the transmitter is rotated, it will still operate in all the various positions of the transmitter. The lever I is elevated upon the removal of the receiver by 5 means of the usual spring acting upon the contact lever I².

It will be seen that by means of this construction the transmitter and receiver may be adjusted to various positions and held 10 therein, and they may be moved up against the wall to be out of the way when not in use, and may then be pulled out to the proper position with relation to the user's mouth, their parts being so arranged that 15 the device is self-adjusting in every particular. When, for example, the parts C or D are moved up or down the part G is rocked so as to keep the cylinder H and the receiver in proper relation to the user, that 20 is to say, to keep the mouth of the transmitter pointing in the right direction. If, for example, the pieces C and D are moved downwardly and the cylinder H were to remain in the same relative position as shown 25 at present in Fig. 1, the mouth of the transmitter would then point down to too great an extent. This is obviated by the piece G which is moved out at the lower end, that is, the end connected to the part D, thus lifting 30 the cylinder H and the transmitter. It will be seen that by this means an automatic adjustment is secured. The spring lift makes this movement easy of accomplishment. The conductors L leading to the receiver are 35 connected with suitable terminals L¹ at the end of the cylinder H so that the movement of the parts in no manner interferes with the electrical connections. The electrical connection to the cylinder H is also such as 40 not to be interfered with by the movement of the parts.

I have described in detail a particular construction embodying my invention, but it is of course evident that the parts may 45 be varied in many particulars, and I therefore do not limit myself to the particular construction shown.

I claim:

1. A telephone apparatus comprising an 50 adjustable bracket, a cylindrical part pivotally connected therewith and provided with a curved neck, the pivot connecting said cylindrical part to the adjustable bracket being in line with the center of the cylindrical part and at an angle to the axis of said 55 cylindrical part, a transmitter rigidly connected with said neck, a pivoted lever connected with said neck so as to move therewith and provided with a circuit varying 60 device, and a receiver hook pivotally connected with said lever.

2. A telephone apparatus comprising an 50 adjustable bracket, a cylindrical part pivotally connected therewith and provided with

a curved neck, a transmitter rigidly connected with said neck, a lever pivotally connected with said cylindrical part and provided with a circuit varying device, and a receiver hook pivotally connected with said lever, said lever and receiver hook located 70 at one side of the pivot about which said transmitter and cylindrical part move, the pivot for said lever being exterior to said cylindrical part.

3. A telephone apparatus comprising an 75 adjustable bracket, a cylindrical part pivotally connected therewith and provided with a curved neck, a transmitter rigidly connected with said neck, a lever pivotally connected with said cylindrical part and provided 80 with a circuit varying device, and a receiver hook pivotally connected with said lever, said lever and receiver hook located at one side of the pivot about which said transmitter and cylindrical part move, said cylindrical 85 part provided with a removable side piece by means of which the interior is exposed, and a signaling device located on said removable side piece.

4. A telephone apparatus comprising an 90 adjustable bracket, a cylindrical part pivotally connected therewith and provided with a curved neck, a receiver hook and lever pivotally connected with said cylindrical 95 part above the pivot about which it moves, the receiver hook and lever being pivotally connected together, the pivot for said lever being exterior to said cylindrical part.

5. A telephone apparatus comprising an 100 adjustable bracket, a receiver and transmitter pivotally connected therewith and provided with a self-adjusting mechanism intermediate the adjustable bracket and said receiver and transmitter whereby the relative position of the two is automatically adjusted as the adjustable bracket is moved to its various positions, said self-adjusting mechanism comprising two parts side by 105 side, one part at an acute angle with the other, one of said parts carrying the receiver and the other part carrying the transmitter.

6. The combination with a telephone transmitter of two pieces placed side by 115 side and pivotally connected at their ends, a frictional clamp connecting them together, a spring lift device carried by one of said pieces and coacting with said frictional clamp, a connecting piece between the transmitter and said pieces pivoted to one piece 120 and having a projection pivoted to the other, the connection between the transmitter and said two pieces being such that the face of the transmitter is in proper position during 125 all its various positions.

7. A telephone apparatus comprising a transmitter rigidly connected to a part piv-

totally connected to a support, a receiver associated therewith, a receiver hook for the receiver, a lever to which said hook is movably connected, said lever pivotally connected to the part carrying the transmitter, and located at the side thereof and extending 5 part way therewith, the connection being

at one side of the axis about which said part moves.

THEODORE SMITH.
